G. BULLOCK.
BATH TUB COVER.
APPLICATION FILED NOV. 8, 1916.

1,262,442.

Patented Apr. 9, 1918.

Attest.

Charles A. Becker.

Inventor:
George Bullock,
by *Charles A. Becker*,
his Attorney.

UNITED STATES PATENT OFFICE.

GEORGE BULLOCK, OF GRAND JUNCTION, COLORADO.

BATH-TUB COVER.

1,262,442.

Specification of Letters Patent. Patented Apr. 9, 1913.

Application filed November 8, 1916. Serial No. 130,110.

To all whom it may concern:

Be it known that I, GEORGE BULLOCK, a citizen of the United States, residing at Grand Junction, Mesa county, and State of Colorado, have invented a new and useful Bath-Tub Cover, of which the following is a specification.

This invention relates to bath tub covers.

An object of the invention is to provide a cover adapted to be applied to the ordinary bath tub and adapted to be adjusted in position thereover in order to prevent the evaporation and cooling of the water so that the heat and steam will be conserved and retained within the tub.

Another object of the invention is to produce a bath tub cover for the purpose mentioned and improved detachable hinge supports adapted to be connected to the tub for retaining the cover in proper adjustment thereon.

An additional object is to provide a bath tub cover comprising a metallic non-corrodible frame provided with hinges and means for detachably connecting them to the tub, the frame supporting a cover adapted to constitute a closure for the tub to retain the heat therein and provided with a space or passage and an apron in connection therewith adapted to fit around the neck and shoulders of the user and to prevent the escape of the heat and steam from within the tub when the device is in use.

Other objects will appear from the following description, reference being made to the accompanying drawing illustrating one embodiment of my invention, in which—

Figure 1 is a plan view of the device applied to a bath tub of ordinary construction.

Fig. 2 is a longitudinal sectional view on the line 2—2 of Fig. 1.

Fig. 3 is a transverse sectional view on the line 3—3 of Fig. 1.

Fig. 4 is an enlarged detail view illustrating the hinge device for securing the cover to the tub.

Fig. 5 is a view looking toward the top of the hinge when in connection with the tub, as illustrated in Fig. 4.

The tub in connection with which I have illustrated the cover is of the usual well known construction having a downwardly curving flange around its upper edge. My improved cover includes a metallic frame 1 preferably in the form of a non-corrodible

wire or rod. The frame includes side portions extending at the sides of the tub and connected by an end portion at the foot of the tub, and it also includes a substantially U-shaped portion in connection with the curving extensions of the side portions of the frame at the head thereof. Bracing wires or rods 2 extend obliquely from points midway between the ends of the sides of the frame to a point midway between the extremities of the end portion of the frame at the foot of the tub and to a connection with the U-shaped portion at the head of the frame, as will be clearly understood by reference to Fig. 1. By this means the sides and ends of the frame are reinforced and strengthened. The frame is provided with a cover 3 of appropriate material such, for instance, as canvas, which is preferably non-absorbent.

The U-shaped portion of the frame supports a depending apron 4 adapted to fit around and upon the neck and shoulders of the user of the tub and to form a substantially close fit to prevent escape of the heat and steam from the tub when the device is in use, it being understood that the neck of the user extends through the U-shaped portion of the frame.

Each side portion of the frame is provided with a number of pairs of lugs 5, the cover being cut to provide sufficient space for the lugs. The hinges employed for connecting the frame to the tub are preferably in the form of spring wires, each having a hook 6 adapted to extend between a pair of the lugs 5, and having hooks 7 adapted to extend around and beneath the curved flange at the top of the tub, substantially as illustrated in Figs. 3 and 4. Each hinge is provided with a clamping screw 8 having threaded connection with the hook 7 and being adjustable to clamp against the under side of the flange at the top of the tub in the manner illustrated in Fig. 4, in order to hold the hinge securely in position and to prevent the cover from becoming displaced when raised or lowered. The hooks 6 passing over the wire frame permit the cover to be raised and lowered and, when the device is not in use, it may be raised and tilted back against the wall leaving the tub uncovered. The provision of the lugs 5 in connection with each side portion of the frame enables the cover to be applied to either side of the tub as required by its location.

In cases where the tub is at a slight distance from the wall the cover may be tilted back against the wall and will be retained in that position by gravity. Instances occur, however, in which the wall inclines over the tub to such an extent that the cover cannot be moved beyond balanced position and will, therefore, not be retained in open position by gravity. In such cases it is desirable to provide, in connection with the frame, an eyelet 9 adapted to be engaged with any proper retaining device secured to the wall. Thus, by this expedient the cover may be retained in open position in any location.

While I have suggested that the cover be made of canvas, I do not restrict myself to the use of that material, nor do I confine myself to the specific construction and arrangement of the other features described, since it is apparent that there may be variations without departure from the principles and scope of the invention.

What I claim and desire to secure by Letters Patent, is:—

1. A device of the character described, comprising a metallic frame arranged to rest upon the upper flange of a bath tub outwardly from the planes of the walls of the tub, a cover for the tub attached to said frame, and clamps pivoted to said frame and engaging the flange of the tub.

2. A device of the character described, comprising a frame arranged to rest upon the upper flange of a bath tub outwardly from the plane of the inner surfaces of the walls of the tub, a cover for the tub attached to said frame, hooks arranged to engage with the flange of the tub, and means for pivotally connecting said hooks with said frame.

3. A device of the character described, comprising a frame of larger area than the top of a bath tub arranged to rest on the upper flange of the tub outwardly from the plane of the inner surfaces of the walls of the tub, a cover for the tub attached to the frame, clamps arranged to engage with the flange of the tub, means in connection with said clamps for pivotally engaging the frame, and means in connection with the

frame preventing longitudinal movement of the frame relative to said clamps.

4. A device of the character described, comprising a frame arranged to rest upon the upper flange of a bath tub, a cover for the tub attached to said frame, hooks arranged to engage the flange of the tub, clamp devices for holding the hooks in connection with the flange of the tub, and means in connection with said hooks for pivotally engaging said frame whereby said frame may be pivotally raised and lowered relative to the tub.

5. A device of the character described, comprising a frame arranged to rest upon the upper flange of a bath tub outwardly from the planes of the walls of the tub, a U-shaped portion in connection with the frame adapted to receive the neck of the user, an apron in connection with the U-shaped portion adapted to fit around the neck and shoulders of the user, a cover for the tub attached to said frame, clamp devices for releasably engaging the flange of the tub, and means in connection with said clamp devices for effecting releasable pivot connection with said frame whereby said frame and the neck may be pivotally raised and lowered relative to the tub.

6. A device of the character described, comprising a frame arranged to rest upon the upper flange of a bath tub outwardly from the planes of the walls of the tub, a U-shaped portion in connection with the frame adapted to receive the neck of the user, an apron in connection with the U-shaped portion adapted to fit around the neck and shoulders of the user, a cover for the tub attached to said frame, clamp devices for releasably engaging the flange of the tub, means in connection with said clamp devices for effecting releasable pivot connection with said frame whereby said frame and the neck may be pivotally raised and lowered relative to the tub, and means in connection with the frame for preventing longitudinal movement of the frame relative to said clamping devices.

In witness whereof, I have signed this specification.

GEORGE BULLOCK.
